 Mason, Hinrich & Lawrence

UNITED STATES PATENT OFFICE.

JOHN B. TARR, OF CHICAGO, ILLINOIS.

IMPROVEMENT IN PLANING-MACHINES.

Specification forming part of Letters Patent No. 55,389, dated June 5, 1866.

To all whom it may concern:

Be it known that I, JOHN B. TARR, of Chicago, in the county of Cook and State of Illinois, have invented a new and Improved Mouth-Piece for Planing-Machines; and I do hereby declare that the following is a full, clear, and exact description thereof, reference being had to the accompanying drawings, making a part of this specification, in which—

Figure 1 is a top view of the improved mouth-piece, showing it operating at two points upon the edge of a board which is being planed or jointed. Fig. 2 is a similar view, showing the mouth-piece pressing upon one point only of the board.

Similar letters of reference indicate corresponding parts in the two figures.

This invention relates to an improvement on the planing-machine patented June 8, 1858, and numbered 20,527, and to the feature therein shown of protecting the face of the stuff during the operation of the cutters by pressure-surfaces.

The object of my invention is to employ, in conjunction with tonguing-and-grooving or jointing cutters or planers, a spring mouth-piece of such form as will support the edge of the board while being cut on both sides of the cutter and prevent the stuff from being slivered by said cutter, said mouth-piece being so applied that it will yield and accommodate itself to inequalities in the width of the stuff without releasing the stuff from pressure, as will be hereinafter described.

To enable others skilled in the art to understand my invention, I will describe its construction and operation.

In the accompanying drawings, A represents a rotary cutter or planer, which may be adapted for jointing or tonguing and grooving the edges of boards.

B represents a mouth-piece, which is of a C shape, and which partially encircles the rotary cutter A, as shown in the drawings. This mouth-piece is pivoted at a to a slide, b, which is allowed a movement at right angles to the line of the stuff in the machine, restrained only by a spring, c, which is of sufficient strength to press the ends of the piece B against the edge of the stuff which is being fed past the cutter, as indicated in the drawings.

I have represented no plan for feeding the stuff through the machine, for the reason that my invention relates only to those parts which support the edge of the board at and near the point of cutting.

The feed-rollers, guides, and frame-work for supporting the planing mechanism may be constructed and arranged as represented in the Patent No. 20,527 aforesaid, or in any well-known manner.

It will be seen by reference to the drawings, Fig. 1, that the stuff is sustained by the mouth-piece B at two points, e f, the stuff being fed past the rotary cutter in the direction indicated by the arrow. At the point e the end of the piece B is reduced so that it will press against the edge of the stuff in such close proximity to the point of cut that this point e will prevent the stuff from being slivered by the cutters.

On the opposite side of the cutter A the end of the piece B terminates in a rounded impinging-surface, which presses against the edge of the stuff after it leaves the cutter and the end e of the yielding mouth-piece, as shown in Fig. 2. This end f of the piece B, together with the end e of the same piece, are allowed to yield and accommodate themselves to the width of different boards; also to inequalities in the width of boards.

By having the mouth-piece B pivoted to a spring-slide, b, as above described, the end e of said piece B will accommodate itself to inequalities in the surface or edges of boards without the end f leaving its bearing. This movement is indicated in red lines, Fig. 2. By means of this yielding C-shaped mouth-piece B a constant pressure is maintained upon the edge of a board on each side of the cutter, and the cutters are prevented from tearing or slivering the stuff, however irregular the edges thereof may be.

I do not confine myself to the precise form of the mouth-piece B, as other forms may be adopted which will operate upon the principle herein set forth; but it is important with my construction to have both the bearing ends e f formed on one piece or stock B B, as shown.

The end f of the mouth-piece will press the stuff closely against the guard and prevent the stuff from springing after it leaves the end e of said mouth-piece.

Having thus described my invention, what I claim as new, and desire to secure by Letters Patent, is—

1. The construction of the mouth-piece B B e f, substantially in the manner herein described and set forth.
2. The arrangement of the mouth-piece B B,

slide b, spring e, in relation to the cutter A, substantially in the manner herein described and shown.

J. B. TARR.
